UNITED STATES PATENT OFFICE.

EDWARD J. McNERNEY, OF KANSAS CITY, MISSOURI.

DESIGN FOR A STATUETTE.

42,607.

Specification for Design.

Patented June 11, 1912.

Application filed April 1, 1912. Serial No. 687,860. Term of patent 3½ years.

To all whom it may concern:

Be it known that I, EDWARD J. McNERNEY, a citizen of the United States, residing at Kansas City, in the county of Jackson and State of Missouri, have invented a new, original, and ornamental Design for a Statuette, of which the following is the specification, reference being had to the accompanying drawing, forming part thereof.

The figure is a perspective view of a statuette, showing my new design.

I claim:

The ornamental design for a statuette, as shown.

EDWARD J. McNERNEY.

Witnesses:

LETA E. COATS,
ARTHUR C. BROWN.
